(57) **CLAIM**

The ornamental design for a headphone wrap including ornamental cat ears, as shown and described.

DESCRIPTION

FIG. 1 is a front perspective view of a headphone wrap including ornamental cat ears, showing my new design; FIG. 2 is a top plan view thereof;

FIG. 3 is a front elevational view thereof showing the headphone wrap including ornamental cat ears in an exemplary environmental context;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing of environmental matter is for illustrative purposes only and forms no part of the claimed design.

1 Claim, 1 Drawing Sheet
